CLAIM

The ornamental design for an interior of an autonomous aircraft as shown and described.

DESCRIPTION

FIG. 1 is a first perspective view of an interior of an autonomous aircraft showing our new design;

FIG. 2 is a front side view thereof;

FIG. 3 is a second perspective view thereof; and,

FIG. 4 is a third perspective view thereof.

The elements shown in broken lines form no part of the claimed design.

The dash-dot lines define the bounds of the claimed design and form no part thereof.

1 Claim, 4 Drawing Sheets
